CLAIM

The ornamental design for a charger for electronic device, as shown and described.

DESCRIPTION

FIG. 1 is a front perspective view of a charger for electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is a front perspective view thereof, shown in an environment of use with an example electronic device.

The evenly-spaced dashed broken lines in the drawings depict portions of the charger for electronic device that form no part of the claimed design.

The unevenly-spaced dot-dash broken lines in the drawings define the boundaries of the claimed design and form no part thereof.

(Continued)

The unevenly-spaced dot-dot-dash broken line showing of an electronic device in FIG. 9 illustrates environmental structure and forms no part of the claimed design.
